UNITED STATES PATENT OFFICE.

CARROLL GALLUP, OF NORWALK, OHIO.

CHAIR.

SPECIFICATION forming part of Letters Patent No. 251,708, dated January 3, 1882.

Application filed August 8, 1881. (No model.)

To all whom it may concern:

Be it known that I, CARROLL GALLUP, of Norwalk, in the county of Huron and State of Ohio, have invented certain new and useful 5 Improvements in Chairs; and I do hereby declare the following to be a full, clear, and exact description of the invention, such as will enable others skilled in the art to which it pertains to make and use it, reference being had 10 to the accompanying drawings, which form part of this specification.

My invention relates to chairs, and more particularly to invalid-chairs; and it consists in the peculiar construction of the same, as will 15 be hereinafter set forth and claimed.

In the drawings, Figure 1 is a side elevation of my chair, showing it so adjusted as to be used as a rocking-chair. Fig. 2 is a side elevation of the same, showing it adjusted for a 20 reclining-chair. Fig. 3 is also a side elevation, showing my chair so adjusted that it may be used as an invalid-chair for the use of persons unable to walk. Figs. 4, 5, 6, 7, and 8 are detached views of different parts, enlarged, in 25 order to show the construction more clearly.

A is a rocker, of which there are two, one on each side.

Pivotaly attached to and extending upward from the forward end of the rocker A is a leg 30 or support, B.

C is the back, which extends down to and is also pivotaly attached to the rocker A, near the center of said rocker.

D is a seat-supporting bar, which is pivotaly 35 attached to the back C, and also to the legs or support B.

E is the seat, which is attached to the bar D in the manner shown in Fig. 6, in which a, b, 40 c, and d are rods of iron or steel, one end of which is bent at right angles and pivotaly attached to the bar D. The other end is rigidly attached to the frame of the seat E, thus making a spring-seat.

F is the chair-arm, pivotaly attached to the 45 back C, and also to a support, i, extending from the bar D.

G is a metal brace, which is pivotaly to the rocker A near its lower end, and provided with a slot, e, and also with an elongated lug, f, 50 which extends from its side, as shown in Fig. 4 of the drawings. The back C is adjustably at-

tached to the brace G by means of a thumb-screw, g, which passes through the slot e, so that the said back may be raised or lowered as desired, and secured in the desired position. 55

H is a bar which is pivotaly attached to the forward leg or support B. Attached to this bar H near its forward end is a large wheel, I, and to a cross-bar, J, which is attached to the rear end of the bar H, is secured caster-wheel 60 K. The inner face of the bar H, adjacent to the brace G, is faced with a piece of iron or steel, h, (see Figs. 4 and 5,) which engages with the lug f on the brace G, and holds the cross-bar H either up, as shown in Figs. 1 and 2, or 65 down, as shown in Fig. 3.

k k' are small levers, which are pivotaly attached to the bar H, and serve to disengage the lug f from the plate h, as shown in Fig. 4. One of these levers, k', is placed a little in 70 advance of the other, in order that one of the said levers will be in position to disengage the lug f no matter at what angle the back C is inclined.

M is a foot-rest, the cleats l of which extend 75 out far enough to engage with an iron rung, m, which passes through the back C at its lower end, where it is pivotaly to the rocker A. The forward end of the foot-rest M is supported on an iron rest, o, which extends from 80 the forward end of the rocker A. This rest o is made in such a manner that the foot-rest M may be raised or lowered, as shown in Fig. 7—viz., the ends of the rest o are bent at right 85 angles and pivotaly attached to rocker A, and may be raised, as shown in Fig. 7, or lowered, as shown by dotted lines in same figure. The ends of the cleats l are secured to the rung m by means of a button, p. (Shown in Fig. 8.) The foot-rest M may be raised higher, as shown in 90 Fig. 8, if desired, it being secured in substantially the same manner as hereinbefore described.

L are iron rods, which are hinged to the cross-bar J, and adapted to engage with the 95 back C, as shown in Fig. 5, when it is desired to strengthen the back.

The operation of my chair is as follows: To adjust the back higher or lower all that is necessary is to loosen the thumb-bolt g, and then 100 either lower or raise the back, and when in the desired position to fasten the thumb-bolt. (See

Figs. 1 and 2.) To change the chair from a rocker, Figs. 1 and 2, to an invalid-chair, Fig. 3, all that is necessary is to disengage the lug *f* from the plate *h* by means of the lever *k*, and then lower the bar *H*, and with it the wheel *I* and caster-wheel *K*, which will act to raise the rockers from the floor, as shown in Fig. 3, when upper end of the plate *h* engages with the lower end of the lug *f* and supports the chair, which rests on the wheels *I* and caster *K*, and may be easily moved from place to place.

In the foregoing specification I have described but one side of my chair; but it is obvious that the other side is constructed in exactly the same manner as the side described.

What I claim is—

1. In a chair, the combination, with the forward leg, of an adjustable bar pivoted to the leg and carrying the wheels *I* and *K*, and provided with levers *h* *h'*, and the rear brace having a lug, *f*, with which said levers are adapted to engage, substantially as set forth.

2. In a chair, the combination, with the back pivoted to the rockers, of a brace pivoted near

the rear end of the rocker and longitudinally slotted, as described, and a thumb-screw, by means of which the back is secured at any desired adjustment, substantially as set forth.

3. The combination, with the chair-back, of the cleat *l*, secured to a rung thereof, the foot-rest *M*, and support *O*, the latter having its ends bent and pivoted to the rockers, so that it may be turned up or down, substantially as set forth.

4. In a chair, the combination, with the rockers and back, of the adjustable bar *H*, carrying the large wheels, the bar *J*, and the slotted brace supporting the back, and provided with a device for locking the back at any adjustment and the bar *H* in either upper or lower position, substantially as set forth.

In testimony whereof I have signed my name to this specification in the presence of two subscribing witnesses.

CARROLL GALLUP.
